UNITED STATES PATENT OFFICE.

GOODRICH Q. LEWIS, OF WHEATON, ILLINOIS, ASSIGNOR TO W. H. MINER, INC., OF CHICAGO, ILLINOIS, A CORPORATION OF DELAWARE.

CUSHIONING WEAR PLATE FOR BUFFER STEMS.

Application filed August 19, 1926. Serial No. 130,137.

This invention relates to cushioning wear plates for buffer stems.

An object of the invention is to provide combined wear and cushioning members to be utilized in connection with the center and side buffer stems of railway cars, and the like to eliminate noise due to vibration between the parts.

A further object of the invention is to provide cushioning members which include exterior metallic plates against which the stems bear during their normal movements, said plates being connected together in such manner to permit limited relative movement thereof, and between which is interposed live rubber held under initial compression thereby, the plates being normally held at the limit of their spreading movement and operating as wear plates which are yieldable to absorb vibration and eliminate noise.

Other and further objects of the invention will more clearly appear from the description and claims hereinafter following.

In the drawings, forming a part of this specification, Figure 1 is a fragmentary top plan view, partly in horizontal section, of a buffering device for railway cars embodying my invention. Figure 2 is a longitudinally vertical sectional view on the line 2—2 of Figure 1. Figure 3 is a transverse, fragmentary, vertical section of the buffering mechanism center stem, taken on the line 3—3 of Figure 2, and showing the invention in elevation. And Figure 4 is a fragmentary sectional view substantially on line 4—4 of Figure 3.

Referring to the drawings, the numeral 10 represents the end platform of a passenger car, provided with a central pocket 11 for the reception of a shock-absorbing mechanism, indicated at 12, against which the usual center stem 13 bears, the opposite forward end of the stem being adapted to abut against a plate 14 mounted upon the buffer proper, indicated at 15. The buffer 15 is supported in position by means of side stems, one of which is shown at 16, there being a coiled spring 17 disposed about the side stem 16, in the customary manner.

The center stem 13 and side stem 16 are slidably carried by the underframe of the platform 10, which may include a forward transversely extending partition indicated at 18, which is provided with a central substantially rectangular opening 19, defined by side walls 20 and 21, top wall 22, and bottom wall

23, the center stem 13 extending through the opening 19, the stem being of a size considerably smaller than the opening as best shown in Figure 3. The bottom wall 23 of the casting is off-set somewhat to provide a shoulder 24, and the metal of the casting to the rear of the wall 22 is provided with a slot 25. The support 26 on the underframe casting may be of any suitable character to support the rear end of the stem 13 while permitting operative movements thereof. The underframe also has a similar arrangement for supporting the side stem 16, and since the invention is applied to the side stem in the same manner as to the center stem the description herein will be directed to the center stem only.

The combined cushioning and wear members are best shown in Figures 2 and 3 and are indicated generally by the reference characters 26 and 27. The wear member 26 as shown is of U-shaped formation, including outer and inner plates 28 and 29. The outer plate 28 may be of any suitable metal, said plate including leg portions 30—30, extending on opposite sides of the center stem 13, and a connecting portion 31 which extends across the top of the stem 13, the plate 28 being of a size as to fit snugly against the walls 20, 21 and 22 of the underframe casting. The inner plate 29 is also U-shaped but smaller in size, so that the legs and connecting member thereof extend in spaced relation with respect to the legs and connecting portion of the member 28, the plate 29 being of such size as to afford suitable clearance for the stem 13. Interposed between the plates 28 and 29 is a pad of live rubber indicated at 32, said pad being substantially co-extensive with the plates 28 and 29. The plates 28 and 29 are secured together by means of a plurality of rivets 33, each of which has its opposite heads countersunk in the outer surfaces of the plates 28—29, the rivets being slidably mounted in the plates so that said plates may be pressed toward each other against the pressure exerted by the pad of rubber 32, while the heads of said rivets limit spreading movement of the plates with respect to each other. The plate 29 is provided along its connecting portion with transversely arranged, upwardly extending flanges 34 and 35, the flange 34 being arranged to abut against the face of the wall 22, while the other flange enters the slot 25 in the underframe casting. By this arrange-

ment, longitudinal and lateral movement thereof is prevented.

The wear member 27 is interposed between the under surface of the stem 13, and the top 5 surface of the supporting wall 23 of the under frame structure. The wear member 27 includes spaced plates 36 and 37 between which is interposed a pad of rubber indicated at 38, the plates being secured together by rivets 10 39 which permit movement of the plates toward each other, but limit movement of said plates away from each other, and hold the rubber under initial compression. The plate 37 is provided with an angular extension 40 which extends downwardly and under the wall 23, and is secured in position by means of a flange 41 which abuts against the shoulder 24 formed by the wall 23.

By the above described arrangement it will 20 be appreciated that the normal longitudinal movements of the stem 13 are permitted, the surfaces of the wear plates adjacent to the stem taking up the wear that will occur between the parts; and due to the arrangement 25 of the plates and rubber held therebetween under initial compression, vibratory movements of the stem, both vertically and laterally, are absorbed, thereby eliminating noise which has been found to be very objectionable 30 in connection with the center and side stems of buffer members. Although not shown in detail, it will be appreciated that the side stems may be provided with an arrangement similar to that described in connection with 35 the center stem, as the operation and purpose of the device is identically the same.

While I have herein shown and described what I now consider the preferred manner of carrying out the invention, the same is 40 merely illustrative, and I contemplate all changes and modifications which come within the scope of the claims appended hereto.

I claim:

1. In a device of the character described, 45 the combination with a support provided with an opening; of an element adapted to move through said opening; and means for absorbing vibration of said element in other directions, said means including live rubber 50 under initial compression interposed between said element and the walls of said opening.

2. In a railway car, the combination with 55 a buffer stem; of supporting structure for said stem, including an opening to permit reciprocation of said stem; and spaced plates surrounding said stem and interposed between the same and the walls of said opening; live rubber interposed between said plates; means connecting said plates for 60 holding said rubber under initial compression while permitting approach of said plates; and means for maintaining said plates

against longitudinal movement with reference to said supporting structure.

3. In a device of the character described, 65 the combination with a longitudinally reciprocal member; of structure for supporting said member for reciprocation, said structure providing an opening, having abutments at opposite sides thereof; spaced U-shaped plates disposed about said member and interposed between the same and the walls defining said opening, said plates being connected to limit recession with respect to each other while permitting approach 70 thereof; cushioning means interposed between said plates; and projections upon said plates adapted to engage the abutments on said structure to prevent movement of said plates longitudinally with reference to said 75 member.

4. As an article of manufacture, combined cushioning and wear members comprising spaced plates, defining a central opening, said plates being connected to restrict spreading 85 movement therebetween while permitting approach thereof, said plates having live rubber interposed between them.

5. As an article of manufacture, combined cushioning and wear plates comprising 90 spaced plates, defining a central opening, said plates being connected to restrict spreading movement therebetween while permitting approach thereof, said plates having cushioning means interposed between them; said 95 cushioning means being in the form of live rubber held under initial compression by said plates.

6. As an article of manufacture, a combined cushioning and wear member, comprising 100 spaced plates, said plates being connected together to restrict spreading movement thereof while permitting approach of the same, said plates having cushioning means interposed therebetween; said cushioning 105 means being in the form of live rubber held under initial compression by said plates.

7. An article of manufacture comprising 110 a pair of spaced relatively movable plates; cushioning means in the form of a live rubber pad held between said plates and filling the space therebetween, said pad being co-extensive in length and width with said plates; means for limiting relative separation of said plates but allowing approach of 115 the same and holding the cushioning means under initial compression; and means engaging and confining said cushioning means on all sides against expansion in the direction of its length and width.

In witness that I claim the foregoing I have hereunto subscribed my name this 17th day of August, 1926.

GOODRICH Q. LEWIS.
